(57) CLAIM

The ornamental design for an armoire, as shown and described.

DESCRIPTION

FIG. 1 is a perspective view of an armoire showing our new design;

FIG. 2 is a front elevation view thereof;

FIG. 3 is a top plan view thereof; and,

FIG. 4 is a right side elevation view thereof, the left side elevation view being a mirror image thereof.

The broken lines shown herein are for illustrative purposes only and form no part of the claimed design.
